ASSIGNORS TO H. MUELLER MANUFACTURING COMPANY, OF DECATUR, ILLINOIS, A COR-
PORATION OF ILLINOIS.

SWING-SPOUT COMPRESSION BASIN-COCK.

No. 879,400.

Specification of Letters Patent.

Patented Feb. 13, 1902.

Application filed May 28, 1900. Serial No. 318,229.

To all whom it may concern:

Be it known that we, PHILIP MUELLER, HENRY MUELLER, and ANTON SCHUEMANN, residents of the city of Decatur, county of Macon, and State of Illinois, have invented a certain new and useful Swing-Spout Compression Basin-Cock, of which the following is a specification.

This invention is exemplified in the structure hereinafter described and it is defined in the appended claims.

The objects of the invention will appear from the following detail description.

In the drawings forming part of this specification Figure 1 is a central section lengthwise through a basin cock embodying our invention, the valve being shown open. Fig. 2 is a broken section exposing essential details of the basin cock and showing the valve closed. Fig. 3 is a central longitudinal section through the stem and valve. Fig. 4 is a plan of the under side of the spout. Figs. 5 and 6 are diagrams illustrating certain capabilities in the use of a pair of basin cocks constructed in accordance with our invention.

The body 1 of the cock is internally screw-threaded and it has the valve seat 2. A cap nut 3 is screwed onto the upper end of the cock body and it contains the packing ring 14, surrounding the valve stem. A metal ring 4 has the downward-extending stop lug 6 and it is clamped between the nut 3 and the upper end of the cock body. A fiber ring 5 is interposed between the upper end of the cock body and the metal ring 4. The valve stem 7 has the external screw threads 8 and a lug 9 extends upward from the threads in position to strike the lug 6 of the metal ring when the valve is open. Above the nut 3, the valve stem is provided with a set of external ribs 10, which engage corresponding depressions in the spout and the upper end of the stem is externally screw-threaded, as shown at 11. A cap 12 is screwed onto the upper end of the valve stem, against the spout, and an indicator button 13 is secured in the upper end of the cap 12. The valve stem has a central bore 18, which forms a passage way for water, and openings 17 and 19 penetrate the wall of the stem and communicate with the bore. The spout 15 has an enlarged hollow end 16 which is adapted to fit over the upper part of the valve stem, and depressions, or corrugations, 18^a are

formed in the inner surface of the lower part 56 of the hollow end of the spout, to fit over the ribs 10 of the valve stem.

A valve 20 is held in the lower end of the valve stem by means of screw 21, and it closes against seat 2, as shown in Fig. 2. The threads 3 of the valve stem, and the corresponding threads of the body, are made double pitch to increase the incline so that the valve may be opened sufficiently without excessive swing of the spout. When the valve is open, as shown in Fig. 1, the water passes the valve seat, enters the bore 18 of the valve stem through openings 17 and discharges into the enlarged hollow end of the spout through holes 19. The metal ring 4 is held in position by pressure and friction and it may be shifted to vary the position of the stop lug 6 by unscrewing the cap nut 3.

The indicator buttons 13 are lettered to show whether the cock is connected with a cold water pipe or a hot water pipe, and a button bearing one inscription may be substituted for a button bearing a different inscription, by unscrewing one cap nut 12 and attaching another nut having a button 30 suitably inscribed. In a pair of cocks, one has a button bearing the word "Hot" and the other has a button bearing the word "Cold". In a pair of cocks, the valve stem of one has a right-hand thread, 8, while the other has a left-hand thread.

In attaching a cock to a slab it is advisable to proceed as follows:—First, take a cock with the parts all properly assembled and turn the spout to close the valve; then place 90 the square shank of the cock into the square hole of the slab with the inscription on the button in position to be easily read, regardless of the direction of the extension of the spout; then unscrew the cap nut 12, remove 95 the spout, extend the spout in the direction it should point when the valve is closed, set the spout over the valve stem in engagement with the ribs 10 thereof and screw the cap nut 12 into its original position. If, by 100 chance, the spout should extend in the desired direction when the cock is first set in position on the slab, the above-described adjustment will, of course, be unnecessary, but ordinarily some adjustment will be needed to get everything in desired shape.

The lug 6 of the metal ring 4 forms a stop for the lug 9 of the valve stem when the valve

is wide open, and it is possible to adjust the position of the lug 6 by turning the ring around the valve stem, after loosening nut 3. This feature of the invention is not indispensable, as ordinarily the user will instinctively swing the spout to the right place to open the valve sufficiently and discharge the water properly into the bowl, but it positively prevents swing of the spout to a position to discharge water onto the slab. If the stop were omitted and the spout of the hot water cock should become so hot as to make a user distrustful about grasping it, he might swing the spout open with a stroke, or push, with the liability of throwing it far enough to discharge onto the slab, and perhaps splatter himself with the hot water.

In the drawings, the stop 6 is set to permit a one-fourth turn of the valve stem. When wear, or other conditions and effects, make it desirable to vary the position of the stop, adjustment is made in the following manner: The spout is turned to shut off the water; the nuts 12 and 3 and the spout 15 are detached; the ring 4 is placed with its lug 6 against the lug 9 of the valve stem, in front thereof; the nut 3 is screwed down close enough to hold the ring in place but not tight enough to prevent it from turning; the spout and cap nut 12 are put in place; the spout is swung in a valve-opening direction until the lug 6 is carried to its desired position, and then, while the spout is held in position with one hand, the other hand is used to screw nut 3 so tight against the ring as to hold the ring and the lug thereon securely in place. Subsequently the spout is swung to close the valve, as a matter of course.

40 The cocks may be attached to a slab in position to swing toward the sides of the bowl in closing, or toward the back of the bowl. These conditions are represented in Figs. 5 and 6, where a slab is shown at 22 and a bowl is shown at 23. In these figures the spouts are shown in valve-closing positions in solid lines and in valve-opening positions in broken lines.

45 The cocks of a pair are rights and lefts, and a change from the position shown in Fig. 5 to that shown in Fig. 6 requires an interchange of cocks, or a shifting of the cold water cock to the hot water side and of the hot water cock to the cold water side. This interchange necessitates a swapping of buttons, which is effected by changing the cap nuts 12, as hereinbefore explained.

50 The number of ribs 10 on the valve stem, and the corresponding depressions 16^a of the spout, may be increased to any extent consistent with sufficient strength to permit manipulation of the valve stem by swing of the spout, and they should be sufficiently fine and numerous to permit nice adjustment 55 of the spout on the stem, both originally

and to compensate for wear. The valve-closing swing of the spout is arrested by contact of the valve with the valve seat, the spout should stop at about the same place each time the valve closes and when the valve wears enough to permit the spout to swing materially past its proper closed position readjustment of the spout and stops may be made, as hereinbefore explained.

What we claim as new and desire to secure 75 by Letters Patent, is:—

1. In a swing-spout compression basin cock, the combination of an internally-screw-threaded body having a valve seat, an externally-screw-threaded valve stem 80 adapted to close at one end against the valve seat and having the other end extending above the body, said valve stem having a passage way leading from above the valve end to above the cock body, and a spout 85 attached to the projecting end of the valve stem, so as to turn therewith, and communicating with the upper end of the passage way through the stem; with means for adjusting the position of the spout around the stem, lugs on the stem and body, and means for adjusting one lug and hence the position of the stem when the lugs engage.

2. In a swing-spout compression basin cock, the combination of an internally-screw-threaded body having a valve seat, an externally-screw-threaded valve stem 95 adapted to close at one end against the valve seat and having the other end extending above the body, said valve stem having a passage way leading from above its valve end to above the cock body, a lug on the stem within said body, a ring adjustable annularly within the body, and a stop lug on the ring adapted to be engaged by that on the stem; 105 with a set of ribs encircling the valve stem above the cock body, and a spout having an end fitting over the projecting end of the valve stem in engagement with the ribs and in communication with the upper end of the 110 passage way.

3. In a swing-spout compression basin cock, the combination of an internally-screw-threaded body having a valve seat, an externally-screw-threaded valve stem adapted 115 to close at one end against the valve seat and having the other end extending above the body, said valve stem having a passage way leading from above its valve end to above the cock body, lugs on the stem and within the body and adapted to engage when the former is rotated and means for adjusting one lug annularly; with a set of ribs formed on the valve stem above the cock body, a spout having an end fitting over the projecting end of the valve stem in engagement with the ribs and in communication with the upper end of the passage way, and a nut 125 screwed onto the upper end of the valve stem and against the spout.

4. In a swing-spout compression basin cock, the combination of an internally-screw-threaded body having a valve seat, an externally-screw-threaded valve stem adapted to close against the valve seat at one end and having its other end extending above the body, said valve stem having a passage way leading from above its valve end to above the cock body, a ring clamped on the upper surface of the body, a stop lug on the ring, means for adjusting the ring and the position of its lug, a lug on the valve stem adapted to engage the lug of the ring, and a spout attached to the projecting part of the valve stem and communicating with the upper end of the passage way through the stem.
5. In a swing-spout compression basin cock, the combination of an internally-screw-threaded body having a valve seat, an externally-screw-threaded valve stem adapted to close against the valve seat at one end and having its other end extending above the body, said valve stem having a passage way leading from above its valve end to above the cock body, a cap nut encircling the valve stem and screwing onto the upper end of the cock body, a ring clamped between the cap nut and the upper surface of the body, a stop lug on the ring, a lug on the valve stem adapted to engage the lug of the ring when the valve is open, and a spout attached to the projecting part of the valve stem, so as to turn therewith, and communicating with the upper end of the passage way through the stem.
6. In a swing-spout cock, the combination with the cock body having a valve seat, the tubular valve stem turning within the body and having lateral inlet and outlet openings, and the valve connected to the stem between said seat and inlet; of the spout adjustably mounted on the stem and communicating with said outlet, and adjustable means for checking the opening of the valve.
7. In a swing-spout cock, the combination with the cock body having a valve seat, the tubular valve stem turning within the body and having lateral inlet and outlet openings, and the valve connected to the stem between said seat and inlet; of the spout adjustably mounted on the stem and communicating with said outlet, and a lug adjustably mounted on the body for checking the rotation of the stem as the valve opens.
